(57) **CLAIM**

The ornamental design for corner bracket for a box frame bed, as shown and described.

DESCRIPTION

FIG. 1 is a front perspective view of corner bracket for a box frame bed of the present invention;

FIG. 2 is a rear perspective view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a left side elevation view thereof;

FIG. 8 is a right side elevation view thereof;

FIG. 9 is a perspective view thereof shown interconnected with portions of a box frame bed; and,

FIG. 10 is another perspective view thereof shown within a box frame bed having three additional corner brackets.

The broken lines in FIGS. 9 and 10 illustrate the environment of a corner bracket for a box frame bed which form no part of the claimed design. The corner bracket for a box frame bed is shown with a symbolic break in its length. The appearance of any portion of the article between the break forms no part of the claimed design.
